(57) **CLAIM**

The ornamental design for a surgical instrument handle, as shown and described.

DESCRIPTION

FIG. 1 is a rear perspective view of a surgical instrument handle;

FIG. 2 is a front perspective view thereof;

FIG. 3 is a rear end view thereof;

FIG. 4 is a front end view thereof;

FIG. 5 is a left side elevational view thereof;

FIG. 6 is a right side elevational view thereof;

FIG. 7 is a top plan view thereof; and,

FIG. 8 is a bottom plan view thereof.

The broken lines in the Figures show portions of the surgical instrument handle which form no part of the claimed design.

1 Claim, 7 Drawing Sheets
